[57] CLAIM

The ornamental design for an integrated running board and mud flap, as shown and described.

DESCRIPTION

FIG. 1 is a perspective view of the integrated running board and mud flap.

FIG. 2 is a front elevational view of the integrated running board and mud flap.

FIG. 3 is a back elevational view of the integrated running board and mud flap.

FIG. 4 is a top elevational view of the integrated running board and mud flap, with the running board tread surface removed for ease of disclosure;

FIG. 5 is a bottom elevational view of the integrated running board and mud flap;

FIG. 6 is an enlarged side elevational view of one end of the integrated running board and mud flap;

FIG. 7 is an enlarged side elevational view of the other end of the integrated running board and mud flap; and,

FIG. 8 is a greatly enlarged sectional view of the integrated running board and mud flap taken along line 8-8 of FIG. 1.
